UNITED STATES PATENT OFFICE.

DENISE SOREL AND MARIE SARLABOUS, OF NEW YORK, N. Y.

LEG GARMENT.

Application filed October 14, 1921. Serial No. 507,634.

To all whom it may concern:

Be it known that we, DENISE SOREL and MARIE SARLABOUS, both residing in New York, county and State of New York, have 5 invented certain new and useful Improvements in Leg Garments, of which the following is a specification.

This invention relates to an improved leg garment, and one of the objects of the invention is to provide a leg covering, particularly adapted for women's use, of such construction that it may be positioned over the shoe and stocking, and have the appearance of a spat or overgaiter, or a cloth top shoe.

Another object of the invention is to provide a leg covering which while affording warmth and protection to the leg of the wearer, is nevertheless neat and attractive 20 in appearance, and has the added advantage of fitting closely about the exterior of the shoe of the wearer, artificial means being provided to cause the garment to take on the appearance of the upper of a shoe, or 25 a boot top or overgaiter.

Other objects and aims of the invention, more or less specific than those referred to above, will be in part obvious and in part pointed out in the course of the following 30 description of the elements, combinations, arrangements of parts and applications of principles, constituting the invention; and the scope of protection contemplated will be indicated in the appended claim.

35 In the accompanying drawing, wherein we have illustrated preferred forms of embodiment of our invention:

Figure 1 is a view in perspective, showing our improved garment positioned upon 40 the leg of a wearer.

Figure 2 is an elevational view, showing our improved garment.

Figure 3 is a similar view of another form of construction; and

45 Figure 4 is a view in perspective, partly broken away, showing a detail of construction.

Referring now to the drawing, wherein 50 similar reference characters refer to similar parts throughout the several views thereof, the reference numeral 1 denotes the body of the garment, which as shown, is formed closely to fit the leg of the wearer, the material thereof being preferably 55 formed of a closely knitted elastic material,

the color of which in the present instance is preferably that usually employed in the manufacture of boot tops or cloth top shoes.

Permanently fastened to the upper open end of the garment, which preferably extends above the calf portion of the leg, is an endless elastic member 2, which if desired may be of ornamental design, as shown in the drawing.

The lower end of the garment, which is 65 open-ended, is provided with a portion 3, which preferably fits over the instep of the wearer, a portion 4 which fits over the heel, and portions 5 and 6 which pass partially under the instep of the wearer, the latter 70 portions being connected by an elastic band or stirrup.

The portions 3 and 4 in the embodiment of our invention shown in Figures 1, 2, 3 and 4 are preferably formed at their lower edges 75 so as to lie adjacent the seam that usually surrounds the upper of a shoe, intermediate the foot portion, and the portion enclosing the ankle, and are also constructed closely to hug or embrace the shoe over which the 80 garment is intended to be worn. If the shoe is what is known as a "low shoe" or "Oxford type" of shoe, the lower end of the garment will overlap the upper edges thereof, giving the latter the appearance of a shoe 85 having a cloth top, or ankle portion.

In order to more closely cause the garment to simulate a cloth top shoe or overgaiter, which usually is made of relatively non-elastic material and has a slit or opening at 90 its lower end to enable it to be drawn over the foot with the shoe thereon we preferably form upon the garment a vertical series of stitches 8, to conform to the shape of buttonholes, and sew buttons 9 in the place or 95 line that would ordinarily be occupied by buttons if the same were sewed upon the garment adjacent the open or split portion which portion of the garment our improved device is intended to simulate. This series 100 of artificial buttons and buttonholes is situated on the outside of the garment, where they are usually employed to close the aforesaid slit provided in overgaiters.

It will accordingly be seen that we have 105 provided a device well adapted to attain, among others, all the ends and objects above pointed out, in a very simple yet efficient manner. The garment when worn will be comfortable to the wearer, enabling the lat- 110

ter to wear stockings of delicate fabrics. It is easily removed, and yet is neat and esthetic in appearance.

As many changes could be made in this construction without departing from the scope of the following claim, it is intended that all matter contained in the above description or shown in the accompanying drawing shall be interpreted as illustrative only and not in a limiting sense.

Having thus described our invention what we claim as new and desire to secure by Letters Patent is:

A garment of the class described, comprising a spat portion of elastic material and an elastic extension integral therewith arranged to fit over the calf of the wearer,

said spat portion being circumferentially continuous and provided upon its exterior with a vertical line of buttons disposed upon its side portion and extending upwardly from a point near its lower edge, a stirrup connecting the lower side edges of the spat portion, and said spat portion having elastic fore and rear extensions constructed and arranged to simulate the top of a shoe.

In testimony whereof, we affix our signatures in the presence of two witnesses.

DENISE SOREL.
MARIE SARLABOIS.

Witnesses:
